COLLAPSIBLE PUSH CHAIR AND THE LIKE

Thomas John Marchant, Tiptree, England

Application April 26, 1939, Serial No. 270,057
In Great Britain July 24, 1938

3 Claims. (Cl. 155—139)

The present invention relates to collapsible push chairs and the like framed seats adapted to be folded into a compact somewhat flat assembly. The object of my invention is to enable a collapsible push chair or seat to be extended and automatically locked into the operative position by a simple single operation.

According to this invention a collapsible push chair or seat is of the type with a readily collapsible or flexible, e. g. canvas strip, seat and back rest secured across a transverse member of a back frame and a seat frame, and is characterised in that the back frame is adjustable in effective length and the said two frames are pivotably connected so that they can be brought close together when collapsed, the back frame having means therewith to lock it in predetermined maximum extended position when the seat is in use.

20 In carrying one form of this invention into practice a collapsible chair comprises a U shaped back frame which is telescopic, and a U shaped seat frame, the said two frames being pivoted on a common axis so that they can be brought close together when collapsed, the telescopic side limbs of the back frame having means to lock them in predetermined maximum extended position when the chair is in use, slidable elements of the telescopic arrangement of the back frame having 25 connected to them ends of a pair of side bars pivoted between their ends to the side limbs of the seat frame whereby said pair of side bars are folded close alongside the side limbs of the seat frame contemporaneously with the collapsing of the structure, said side bars carrying at their ends remote from said slidable elements a pair of wheels or other suitable ground engaging members to form two points of support, the other necessary pair of wheels or ground engaging 30 members being carried in juxtaposition to the pivoted connection of the back and seat frames, the transverse parts of the two U shaped frames having connected across them a flexible seat and back rest.

45 In order that this invention may be clearly understood and readily carried into effect a sheet of drawings is appended hereto illustrating an embodiment thereof, and wherein:

Fig. 1 is a side elevation view of the push chair 50 in the operative condition.

Fig. 2 is a rear elevation of Fig. 1.

Fig. 3 shows in side elevation the push chair half opened.

Fig. 4 shows in side elevation the push chair 55 nearly completely folded.

Fig. 5 is a broken detail plan view of the foot rest.

Fig. 6 is a part sectional side elevation of a modification in which the frame elements are 5 composed of tubular metal.

Fig. 7 is a detail broken side elevation showing the seat frame and a co-operating front wheel carrying frame partly folded.

Fig. 8 is a side elevation showing the seat folded, and 10

Fig. 9 is a detail broken side elevation view showing a modification in which the seat frame as well as the back frame is telescopic.

Referring to the drawings the back rest of the collapsible push chair has upper parts 1 joined 15 by a transverse upper member 2 across which and a transverse member 3 joining side limbs 4 of a seat frame is secured the length of fabric or the like 24 forming the flexible seat and back rest.

20 The side limbs 4 of the seat frame are pivoted at their free ends to an axle 5 carrying within said side limbs the rear pair of wheels 6. The free ends of the upper parts 1 carry a pair of rectilinear collars 7 which slide along a pair of 25 lower parts 8 of the back frame. The lower parts 8 are located close alongside the side limbs so as to be in linear continuity therewith and pivoted at their lower ends to said rear axle 5. These lower parts 8 consequently form with the upper 30 parts 1 joined by transverse member 2 an extensible back frame.

Pivoted by pins 9a to the said pair of collars 7 are the rear ends of a pair of supporting limbs 9 which are longer than the side limbs 4 of the 35 seat frame and are bridged at their front ends by a front axle 10 carrying the front pair of wheels 16. When the push chair is collapsed these supporting limbs 9 lie close alongside the side limbs 4 of the seat frame, and they are pivoted by riveted-over pins 11 or their equivalent to such side limbs at a point slightly in rear of the centre of said side limbs. By this means when the push-chair is opened out, supporting limbs 9 and the side limbs 4 of the seat frame 40 intersect X fashion as shown in Fig. 1.

45 At the front ends of the side limbs 4 are a pair of upstanding lugs 12 and connected to these lugs are the front ends of a pair of break-back or like links 13, e. g. two pairs of bars, one pair 50 each side, each pair of bars being pivoted together at one end by a pivot pin 14, and one being pivoted at its other end to the appropriate lug 12, and the other forming an arm rest, being pivoted at its other end by a pin 15 to the upper 55

part 1 of the back frame at a point which is shown in Fig. 4 as just in front of the free end of the adjacent lower part 8 of the back frame when the chair is collapsed. By this means when the 5 push chair is collapsed the arm rest bars of the double links 13 fold close alongside the bars of such links which are pivoted to said lugs 12, and when the push chair is opened out, these two 10 pairs of bars form substantially L shaped side 10 arms.

The push chair is opened out simply by holding down the back axle and pulling up on the transverse member 2 forming upper parts 1 of the back frame, the angle of movement relatively 15 to the plane supporting the wheels being about a right angle. Locking pins 17 are carried by the cranked ends 19 of a transverse bar 20 slidably supported in bent lugs 21 affixed to and depending from a horizontal bar 22 secured at its 20 cranked ends 22a to the upper ends of the lower parts 8 of the back frame by riveted pins 23. The locking pins 17 are adapted to trip into apertures 18 in the lower parts 8 of the back frame via similar apertures in the upper parts 1, so as to 25 lock the upper and lower parts in maximum extended position. Apertures 29 similar to apertures 18 are provided in the upper parts 1, the pins 17 being adapted to trip into the apertures 29 via the apertures in the lower parts 8 to lock 30 the push-chair in the collapsed position, i. e. the position in which the upper and lower parts of the back frame are at minimum extension.

The seat and back rest can as before said, be 35 a length of fabric 24 or other suitable material with tubes at its ends fitted over the transverse members 2 and 3 of the seat and back frames. It will be seen that the upper or free ends of the lower parts 8 are bridged by the bar 22, and it is preferred to pass the length of fabric or the 40 like 24 under this bar 22.

If desired a suitable foot rest panel 25 can be supported by side angle bars 26 upon the front axle 10 and a transverse bar 27 secured by crank ends 28 to the normally front lower ends of the supporting limbs 9.

The invention is not necessarily limited to 45 wheeled chairs, as feet may be provided instead of wheels.

In the modification shown in Figs. 6 to 8 inclusive, instead of having two overlapping upper and lower parts 1 and 8 for the extensible back frame, the upper parts 1 are tubular and in their lower ends slide tubular lower parts 8 which have apertures (not visible) to receive the locking pins 17.

Also the frame 4 and a frame 9 taking the place of the before said supporting limbs 9, are of tubular metal, the lower or rear ends of the side limbs 4 being bifurcated as at 4a to receive 50 pivotally a pair of cranks 30 fixed to the axle 5.

The frame 9 preferably has a rubber sleeve 31 fitted over its front end which extends beyond the wheels 16, and the front axle also having a pair of rubber sleeves 32 thereon thereby affording a comfortable foot rest. The rear ends of the frame member 9 are flattened to engage in U shaped brackets 33 welded to the lower ends of the frame 1 and having pivot pins 34 passed therethrough.

Instead of having the folding link arrangement 70 of arm rests shown in Fig. 1, these can be omitted and a pair of side or shoulder members 35 of U configuration can be welded to the side members of the frame 1.

To facilitate folding and unfolding the seat, 75

and also to act normally as an emergency brake, a brake lever 36 can be pivoted between its ends to a U shaped brake bar 37 pivoted to the pivot pins or bolts 11, one end of the lever 36 forming a finger piece 36a, and the other end being 5 cranked laterally outwards as at 38 to afford a cam action against a metal bearing strip 39 affixed to the appropriate side limb 4. A coiled tension spring 40 is connected across the appropriate side limb 4 and the U shaped brake 10 member and snaps the brake on when the cranked end of the brake lever is disengaged from the said bearing strip. The brake is a rubber or other suitable sleeve 41 on the cross member of the U shaped bar 37. 15

If desired the seat frame may be extensible, and such an arrangement is shown in Fig. 9, in which the tubular side limbs 4 of the seat frame receives slidably tubular co-axial extensions 4b. The inner elements 4b can be locked to the element 4 by a locking device 4c similar to the locking device constituted by the transverse part 20 and associated elements.

I claim:

1. A collapsible chair which comprises a back 25 frame having extensible uprights formed of slidably connected upper and lower parts and a transverse member joining said upper parts, means for locking said parts in a position of predetermined maximum extension, a seat frame 30 having side limbs joined by a transverse member, supporting limbs pivoted between their ends and on a common axis to said side limbs at points between the ends of the latter, said supporting limbs and side limbs being pivoted on common 35 axes near their extremities to the upper and lower parts of said uprights respectively, and a length of flexible material extending between said transverse members to form a seat and back rest, the arrangement being such that as said 40 uprights are reduced in length said seat frame, back frame and supporting limbs are brought close together.

2. A collapsible chair which comprises a back 45 frame having extensible uprights formed of slidably connected upper and lower parts and a transverse member joining said upper parts, means for locking said parts in predetermined 50 positions of maximum and minimum extension, a seat frame having side limbs joined by a transverse member, supporting limbs pivoted between their ends and on a common axis to said side limbs at points between the ends of the latter, said supporting limbs and side limbs being pivoted on common axes near their extremities 55 to the upper and lower parts of said uprights respectively, and a length of flexible material extending between said transverse members to form a seat and back rest, the arrangement being such that as said uprights are reduced in length 60 said seat frame, back frame and supporting limbs are brought close together.

3. A collapsible chair which comprises a back 65 frame having extensible uprights formed of slidably connected upper and lower parts and a transverse member joining said upper parts, means for locking said parts in predetermined 70 positions of maximum and minimum extension, said means comprising spring loaded pins mounted for transverse movement with regard to said uprights and each adapted to trip in an aperture in one of said lower parts via either of a pair of similar apertures in the corresponding upper part, a seat frame having side limbs joined by a transverse member, supporting 75

limbs pivoted between their ends and on a common axis to said side limbs at points between the ends of the latter, said supporting limbs and side limbs being pivoted on common axes near their extremities to the upper and lower parts of said uprights respectively, and a length of flexible material extending between said trans-

verse members to form a seat and back rest, the arrangement being such that as said uprights are reduced in length said seat frame, back frame and supporting limbs are brought close together.

THOMAS JOHN MARCHANT.
